LIPSTICK CONTAINER

Thomas F. Slater, Waterbury, Conn., assignor to Scovill Manufacturing Company, Waterbury, Conn., a corporation of Connecticut

Application April 25, 1957, Serial No. 45,885

Term of patent 7 years

(Cl. D86—10)

Fig. 1

Fig. 1 is a side view of a lipstick container showing my new design.

Fig. 2 is a top view thereof, and

Fig. 3 is a sectional view taken along line 3—3 of Fig. 1 showing the dot-design elements formed into the outer container shell.

I claim:

The ornamental design for a lipstick container, as shown.
